UNITED STATES PATENT OFFICE.

DANIEL B. DANIELSON, OF MILWAUKEE, WISCONSIN.

BUILDING CONSTRUCTION.

Application filed January 11, 1926. Serial No. 80,593.

This invention relates to improvements in building construction.

It is one of the objects of the present invention to provide a practical and easily arranged metal lath tie-to insert.

In building construction and particularly in the casting of concrete beams various means are adopted for the provision of an insert to which the metal laths or plaster base may be tied or secured or to hang anything desired. All of the means now in common use are open to objections in that an undue amount of material is used, an excessive amount of time is consumed in the installation, and the tie-to means are not always readily concealed.

It is, therefore, the primary object of the present invention to provide a plaster base tie-to insert which will eliminate the foregoing objections and which does not add appreciably to the construction expense.

A further object of the invention is to provide a building construction which is very simple, is strong and durable, and is well adapted for the purposes described.

With the above and other objects in view the invention consists of the improved building construction, and its parts and combinations as set forth in the claims, and all equivalents thereof.

In the accompanying drawing in which the same reference characters indicate the same parts in all of the views:

Fig. 1 is a longitudinal sectional view of a soffit board and concrete beam with a tie-to wire inserted therein;

Fig. 2 is a perspective view of a concrete beam, showing the plaster finish, the plaster base, and the tie-to;

Fig. 3 is a cross-sectional view of a concrete beam and the manner in which the plaster base is secured thereto; and

Fig. 4 is a view showing a modified form of the invention.

The invention, as set forth, is associated with building construction, and particularly the construction of concrete beams. In casting concrete beams it is common practice to utilize a soffit board which is a form for the bottom face of the beam.

In carrying out the present invention a soffit board 5, provided with an elongated slot 6 is used and the tie-to or anchoring rod 7 is inserted in said slot, as shown in Fig. 1.

The tie-to rod or anchoring member 7 is 55 in the form of an elongated rod having spaced apart looped or off-set portions 8. After the concrete has set to form the beam and the soffit board is removed the member 7 will be permanently attached to the beam 60 as shown in Figs. 2 and 3, the looped portions 8 being embedded therein. It will also be noted that there is clearance between the rod and the bottom of the beam to permit tying, as will later be explained, this clearance being due to the depth of the slot 6 in the soffit board.

In connection with the tie-to rod, any form of plaster base may be used and particularly metal laths. As shown in Fig. 3 70 the plaster base members or laths 9 are positioned against the underside of the rod 7 and are tied thereto by tie wires 10 which are bent about the rod and lath. Then, the laths are plastered in the usual manner and the rod and tie wires are covered, as shown in Fig. 2.

In the modified form of the invention shown in Fig. 4, the members 7' are short in length so that the shanks may be bent about 80 the laths as shown, thereby eliminating the use of the wires.

From the foregoing description it will be seen that the invention provides a novel and effective means for securing a plaster base 85 to a concrete beam in building construction.

What I claim as my invention is:

1. In a building construction, a cast member, an elongated non-yielding rod formed with off-set portions, the off-set portions 90 being embedded in said cast member, and the entire rod portion being spaced from the surface of the cast member, and a plaster base tied at spaced points to said rod.

2. In a building construction, a concrete 95 beam, an elongated non-yielding rod extending longitudinally with said beam and formed with off-set portions, the off-set portions being cast into said beam and the entire longitudinal portions of the rod being 100 spaced from the face of said beam, a plaster base, independent ties embracing the base and encircling the rod and plaster covering the outer surface of said plaster base.

In testimony whereof, I affix my signature.

DANIEL B. DANIELSON.
